UNITED STATES PATENT OFFICE

CHARLES S. BUSHNELL, OF ROCHESTER, NEW YORK, ASSIGNOR TO GENERAL RAILWAY SIGNAL COMPANY, OF ROCHESTER, NEW YORK

TRAIN CONTROL SYSTEM FOR RAILROADS

Application filed August 7, 1930. Serial No. 473,522.

This invention relates to train control systems, and more particularly to acknowledging apparatus for such systems.

In the application of automatic train control to railway systems, and particularly automatic train control of permissive type, it has been found expedient to require the engineer to operate suitable acknowledging means to manifest his vigilance and his recognition of the passage of his train by a signal at caution or stop. This acknowledging apparatus is usually a device for preventing a restriction in the progress of the train if manually operated at the proper time. In order to prevent the engineer misusing this apparatus, as by tying it down, it has been found expedient to limit the time during which this acknowledging device may assume its active position by imposing a penalty if it is maintained active too long. This penalty in some cases resided in bringing the train to a stop in the event the device were held in its active position longer than a predetermined period of time. Acknowledging apparatus protected only in this way is not entirely safe, because it would be possible for the engineer to hold his acting device in its active condition substantially continuously, in that if he intermittently allowed it to assume its inactive position momentarily at time intervals less than said first mentioned interval of time the engineer could perform the acknowledging act without observing the condition of the wayside signal. In order to afford better protection against misuse of the acting device, it is proposed in accordance with the present invention to permit functioning of the apparatus only at intervals of time greater than said first mentioned interval of time.

Other objects, purposes and characteristic features of the present invention will in part be obvious from the accompanying drawing and will in part be more specifically pointed out hereinafter.

In describing the invention in detail reference will be made to the single drawing showing conventionally the car carried and trackway apparatus of a train control system of the intermittent inductive type, to

which the present invention has been shown applied.

Referring to the drawing the train control system disclosed therein is generally of the type as shown in my prior Patent No. 1,686,434 dated October 2, 1928, upon which system has been superimposed the improved acknowledging apparatus of the present invention. The car carried apparatus includes the normally energized electro-pneumatic valve EPV, which if de-energized applies the brakes or restricts the train in any other suitable way, the primary relay R¹, the secondary relay R² and the main relay R³, which relays are controlled through the medium of the secondary coil S of the car carried receiver IR, through the medium of flux emitted by the primary coil P. This car carried apparatus also includes the acknowledging relay A, the acknowledging device Ack including time element devices T¹ and T² and the whistle valve WV.

The trackway apparatus includes a wayside signal WS controlled in accordance with traffic conditions in advance in the usual manner, a line relay LR similarly controlled, and an inductor TE which is normally held inactive by having its winding W short circuited through a front contact 1 of the line relay LR, and which inductor if active will induce a voltage impulse in the secondary coil S of the car carried receiver IR upon passage of such receiver over said inductor. Having now briefly described the various elements of the car carried and trackway apparatus, it is believed expedient to discuss the normal condition of the apparatus and the manner in which the acknowledging device Ack must be operated to avoid a brake application.

Operation

The train control device EPV is normally energized through the following circuit:—beginning at the terminal (+), front contact 2 of the relay R², wires 3, 4, and 5, front contact 6 of the relay R³, wires 7, 8, and 9, contact 10 of the reset push button Res, wire 11, normally closed timing contact Z of the acknowledging contactor Ack, wire 12, winding of the device EPV, to the other terminal

(-) of a suitable source of current on the train.

Similarly, the main relay R^3 and the primary coil P of the car carried inductor IR are normally connected in series through the following energizing circuit:—beginning at the terminal (+), front contact 2 of the secondary relay R^2 , wires 3, 4 and 5, front stick contact 6 of the relay R^3 , wires 7 and 10 13, winding of the relay R^3 , wires 14 and 15, primary coil P to the other terminal (—) of the same battery. Attention is directed to the fact that the main relay R^3 not only serves to control the flow of current to the 15 electro pneumatic valve EPV , but also serves as a check against failure of the circuit supplying current to the primary coil P , this because the relay R^3 is connected in series with the primary coil P . Furthermore, since 20 the main relay R^3 is of comparatively low resistance as compared to the primary coil P the potential drop across the relay R^3 , is low and may be used as a source of current for energizing the primary relay R^1 , from 25 which it will appear that the primary relay R^1 will be energized by a current proportionate to the current flowing through the primary coil P , this being an important feature of the car carried apparatus as more 30 fully described in my prior patent above mentioned.

The primary relay R^1 is connected in series with the secondary coil S of the inductive car element IR , and is energized by the drop of 35 potential across the relay R^3 through the following circuit:—beginning at the left hand terminal 13 of the relay R^3 , wires 8 and 16, front stick contact 17 of the relay R^1 , wires 18 and 19, secondary winding S of the receiver IR , wires 20 and 21, winding of the 40 primary relay R^1 , wire 22, back to the other terminal 14 of the relay R^3 .

The secondary relay R^2 is normally energized through the following stick circuit:—beginning at the terminal (+) of said car battery, front stick contact 2 of the relay R^2 , wires 3, 4, and 5, front contact 6 of the relay R^3 , wires 7, 8, and 16, front contact 17 of the relay R^1 , wire 24, winding of the relay R^2 , to the other terminal (—) of said car battery. The acknowledging relay A is slightly slow acting as conventionally shown, and is normally energized through the following circuit:—beginning at the terminal (+) of said car battery, timing contact 25 of the timing device T^2 , wires 26 and 27, winding of the relay A to the other terminal (—) of said battery.

It may be pointed out here that the stopping influence is transmitted from the trackway to the car carried apparatus of the present system upon passage of the car by the trackway inductor TE , the choke coil W of which is open circuited, by the receiver IR being quickly and momentarily bridged by

the track inductor TE , thereby causing a sudden increase in flux through the secondary coil S which change of flux causes an electromotive force to be induced in the circuit of coil S opposing the flow of current in the relay R^1 to a point where this current is insufficient to maintain the relay R^1 energized, thereby opening its stick contact 17 for remaining de-energized until specially restored. It is of course understood that passage of the car element IR over the track element TE when the choke coil W of the track element is closed in a circuit of low resistance will have no effect on the car carried apparatus. 70 75

Let us now assume that the railway car equipped with the car apparatus shown in the drawings passes by the track inductor TE with its winding open circuited, and let us observe how the brakes are applied on the assumption that the engineer has failed to 80 operate the acknowledging device Ack . Passage of the receiver IR over the inductor TE under the conditions assumed, causes a counter electromotive force to be induced in the circuit of the primary relay R^1 , thereby 85 causing this primary relay R^1 to be de-energized and in turn effecting de-energization of the relay R^2 . 90

Dropping of the relay R^2 by the opening of its contact 2 removes energy from the relay R^3 and the primary coil P and also cuts energy off of the train control device EPV , so that movement of the train will be restricted in a manner dependent on the construction of the device EPV , as by a brake application, which restriction can only be removed by the operation of the reset device Res , only accessible from the ground. 95

Let us now assume that the engineer after bringing the train to a stop, steps to the ground and operates the reset device Res . In so doing, the main relay R^3 will be picked up through the following pick-up circuit:—beginning at the terminal (+), contact 10 of the reset device Res , wires 9, 8 and 13, 100 winding of the relay R^3 , wires 14 and 15, primary coil P to the other terminal (—) of said car battery. Since there is now a potential drop over the relay R^3 , and with the reset push button Res still depressed, the primary relay R^1 is connected across the relay R^3 through the following circuit:—beginning at the left hand terminal 13 of the relay R^3 , wire 8, contact 30 of the reset device Res , wires 31 and 21, winding of the 110 relay R^1 and wire 22, back to the right hand terminal 14 of the relay R^3 . With the relay R^1 once energized its stick circuit including the secondary winding S , heretofore traced, is again closed. With the relay R^1 115 again picked up and with the reset push button Res still depressed the secondary relay R^2 is picked up through the following circuit:—beginning at the terminal (+), contact 10 of the reset push button Res , wires 120 125

9 and 16, front contact 17 of the relay R^1 , wire 24, winding of the secondary relay R^2 . With the relay R^2 now energized and its contact 2 closed current may flow to the relays R^1 , R^2 and R^3 and to the primary coil P and also to the device EPV, so that the reset button Res may be released, and the car carried apparatus is restored to its normal condition.

10 Let us now assume that the train approaches the signal 7 at caution or stop and that the engineer is vigilant and operates his acknowledging handle Ack to the dotted position. Under the conditions of traffic assumed the relays R^1 and R^2 will be de-energized in exactly the same manner as heretofore described, but the main relay R^3 will remain energized through the medium of the following auxiliary circuit including the acknowledging contact X —beginning at the terminal (+), winding of the whistle valve WV, wire 32, acknowledging contact X , wire 33, front contact 34 of the acknowledging relay A, wires 35, 4 and 5, front contact 6 of the relay R^3 , wires 7 and 13, winding of the relay R^3 , wires 14 and 15, primary coil P to the other terminal (-) to the car battery. So long as current flows through the circuit just traced the whistle valve WV will sound thereby informing the engineer that a stop influence has been transmitted from the trackway to the vehicle and that he has passed a signal at caution or danger.

Also, during this acknowledging period the device EPV is held energized through the following circuit—beginning at the terminal (+), whistle valve WV, wire 32, acknowledging contact X , 33, 34, 35, 4, 5, 6, 7, 8, 9, 10, 11, contact Z , 12, winding of the EPV to the other terminal (-). It may be pointed out here that operation of the acknowledging device Ack to its dotted position will effect closure of the contacts X and Y through the medium of the arm 37 having a pin 38 operating in the slot of the arm 39. Also, that movement of the acknowledging handle Ack to the dotted position will cause the piston 40² in the timing device T^2 to be moved toward the right thereby opening the contact 25. Also, movement of the lever Ack to the dotted position closes the contact 41 included in a stick circuit of the acknowledging relay A containing the stick contact 42 or relay A, and the wires 43 and 44. The relay A is sufficiently slow dropping so that movement of the acknowledging handle to its normal dotted position in the usual way will allow the contact 41 to be closed before the contact 25 opens, so that the acknowledging relay A will remain energized during the act of acknowledgement.

Not only does operation of the acknowledging contactor Ack to its dotted position complete circuits for maintaining the device R^3 and EPV energized but the following pick-up

circuit for the relay R^1 is also completed:—beginning at the terminal (+), winding of the valve WV, wire 32, contact X , wire 33, contact 34 of relay A, wires 35, 4 and 5, front contact 6 of relay R^3 , wires 7 and 55, back contact 56 of relay R^2 , wire 57, front contact 58 of relay A, wire 59, acknowledging contact Y , wires 60 and 19, secondary coil S, wires 20 and 21, winding of the relay R^1 to the junction between relay R^3 and primary coil P so that the potential drop across relay R^3 is applied to the pick-up circuit for relay R^1 . This will of course pick up relay R^1 ; which relay R^1 will in turn pick up the relay R^2 , after which the acknowledging handle Ack may be returned to normal.

As soon as the train has passed the active track inductor TE the engineer may return his acknowledging handle Ack to its normal position and if he does this in less than a predetermined time, preferably ten seconds, the contact Z included in the energizing circuit of the device EPV will not be opened. If, on the other hand, the acknowledging handle Ack is held in its dotted position of a longer than this predetermined period of time, the contact Z will be opened by action of the spring 50¹ moving the piston 40¹ into the cylinder of the timing device T^1 to a point where the contact Z is opened, so that an automatic application of the brakes or the like, will occur. The specific time element devices T^1 and T^2 illustrated include adjustable vent valves 51¹ and 51², whereby the time of opening the contact Z and the time of reclosing of the contact 25 after operation and return to normal, respectively, of the acknowledging handle Ack may be accurately adjusted. In practice, the timing device T^2 is preferably so adjusted that the contact 25 will not reclose until a much larger interval of time has elapsed, than the time required for contact Z to open, such for instance as 30 seconds, after the acknowledging handle Ack has been returned to its normal position. Also, as will be noted from the drawing the pistons 40¹ and 40² are pistons of the valve type which may be freely drawn out but which are airtight for the return movement, so that they serve the double function of a valve and piston. From this it will appear that the acknowledging relay A will remain deenergized after each operation and return to normal of the acknowledging handle Ack for a period of 30 seconds, and since the contact 34 of this relay A must be closed in order to permit the acknowledging act to become effective, the acknowledging apparatus of the system under consideration is available for use only once during each period of 30 seconds of time. In other words, since the engineer can render the acknowledging apparatus effective only once during a 30 second interval time it behooves the engineer to carefully observe the wayside signals and indicators

120
125
130

and operate the acknowledging device at the time or just before the car carried element IR passes over the track element TE, this because he is permitted to move the acknowledging handle *Ack* only once for each inductor, considering the speed that a train ordinarily moves and considering the ordinary length of the blocks employed.

Although the time devices T^1 and T^2 have been conventionally illustrated as timing devices of the dash-pot type it is to be understood that the invention is not limited to the employment of time element devices of this construction, and that time element devices of the thermal element and clock work type may be employed if desired.

Having thus shown and described one particular species of acknowledging apparatus embodying the present invention and having shown it applied to an intermittent type of system of automatic train control, it is desired to be understood that acknowledging apparatus embodying the present invention may also be applied to continuous inductive type train control systems, for instance of the type as shown in the prior patent to W. K. Howe, No. 1,593,554, granted July 20, 1926, and that various changes modifications and additions may be made to the acknowledging apparatus embodying the present invention to adapt it to the particular type of train control system in connection with which it is to be used, all without departing from the spirit or scope of the present invention or the idea of means underlying the same except as demanded by the scope of the following claims.

What I claim as new is:

1. In a train control system, a brake control apparatus on a vehicle, traffic controlled means partly on the vehicle and partly on the track for governing said apparatus in accordance with traffic conditions, and manually operable means having a limited interval of time of effective operation for maintaining the apparatus inactive independently of its control by said traffic controlled means, said manually operable means being effective only at intervals spaced apart a predetermined period of time and then only when said brake control apparatus is in its normal inactive condition.

2. In combination, a railway vehicle, a normally energized electrically operated brake control device energized by a stick circuit including its own front contact, control means for momentarily breaking said stick circuit under adverse traffic conditions ahead, and acknowledging means for closing an auxiliary circuit for said brake control device effective for a limited time only and rendered available for use only once during a greater period of time.

In testimony whereof I affix my signature.

CHARLES S. BUSHNELL.
